US0D1052327S

(12) **United States Design Patent** (10) Patent No.: **US D1,052,327 S**
(45) Date of Patent: ** Nov. 26, 2024

(54) **COOKING STOVE**

(71) Applicant: **Huizhou Haorui Hardware Technology Co., Ltd**, Huizhou (CN)

(72) Inventors: **Yong Zhang**, Huizhou (CN); **Chaosen Wang**, Huizhou (CN)

(73) Assignee: **Huizhou Haorui Hardware Technology Co., Ltd**, Huizhou (CN)

(**) Term: **15 Years**

(21) Appl. No.: **29/878,598**

(22) Filed: **Jun. 25, 2023**

Related U.S. Application Data

(62) Division of application No. 35/515,175, filed on Sep. 9, 2022 (U.S. filing date under 35 U.S.C. 384), and having an international filing date of Sep. 9, 2022, now Pat. No. Des. 1,000,189.

(57) **CLAIM**

The ornamental design for a cooking stove, as shown and described.

DESCRIPTION

FIG. 1 is a front view of a cooking stove, showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a front perspective view thereof.

The broken lines in the drawings illustrate the portions of the cooking stove, which form no part of the claimed design.
